CLAIM

Feb. 12, 2016 (CN) 2016 1 0084097
 Mar. 11, 2016 (CN) 2016 3 0069454
 Jul. 1, 2016 (CN) 2016 3 0296544
 Jul. 3, 2016 (CN) 2016 3 0299672

The ornamental design for a display screen or portion thereof with keyboard graphical user interface, as shown and described.

(51) **LOC (11) Cl.** **14-04**
 (52) **U.S. Cl.**

DESCRIPTION

USPC **D14/485; D14/488**
 (58) **Field of Classification Search**
 USPC D14/485-495; D20/11; D21/324, 325
 CPC G06F 3/048; G06F 3/0481; G06F 3/04817;
 G06F 3/0482; G06F 3/0483; G06F 3/04842; G06F 3/0485; G06F 3/0486;
 G06F 3/04855; G06F 3/04883; G06F 3/0488; G06F 3/04886; G06F 9/4443;

FIG. 1 is a front view of a first embodiment of a display screen or portion thereof with a keyboard graphical user interface showing my new design.

FIG. 2 is a front view of a second embodiment thereof, and, FIG. 3 is a front view of a third embodiment thereof. The broken line showing of a display screen with graphical user interface is included for the purpose of showing portions of the article which form no part of the claim.
